US00D598911S

(12) **United States Design Patent**
Wang et al.

(10) **Patent No.:** US D598,911 S
(45) **Date of Patent:** ** Aug. 25, 2009

(54) **ALL IN ONE COMPUTER**

(75) Inventors: **Qun Wang**, Shenzhen (CN); **Yun-Lung Chen**, Taipei Hsien (TW); **Zhen Zhang**, Shenzhen (CN); **Hong-Jin Wu**, Shenzhen (CN)

(73) Assignee: **Hon Hai Precision Industry Co., Ltd.**, Tu-Cheng, Taipei Hsien (TW)

(**) Term: **14 Years**

(21) Appl. No.: **29/321,034**

(22) Filed: **Jul. 9, 2008**

(51) LOC (9) Cl. **14-02**

(52) U.S. Cl. **D14/336**; D14/371

(58) Field of Classification Search D14/371-376, D14/125-129, 336-337, 356; 248/917-924, 248/176.1, 278.1; 341/12; 345/104, 156, 345/173, 174, 901-905; 348/180, 184, 325, 348/739; 361/680-686, 679.08, 679.23; 349/1, 2, 11, 58

(57) **CLAIM**

The ornamental design for “all in one computer,” as shown and described.

DESCRIPTION

FIG. 1 is a perspective view of the all in one computer showing our new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of “all in one computer” is for the purpose of illustrating environmental structures only and forms no part of the claimed design.
